UNITED STATES PATENT OFFICE

GEORGE G. ALBERT, OF NEW YORK, N. Y.

CEMENTING MACHINE

Application filed March 18, 1931. Serial No. 523,132.

This invention relates to a machine designed for applying cement between thicknesses of strip material and subsequently pressing the materials together so that they will be caused to adhere.

The primary purpose of the invention is to apply sheets of cork to back boards of wood, composition or the like although, obviously, it can be employed for joining other kinds of materials, one of which is of a flexible nature.

Another object of the invention is to provide an apparatus which can supply the adhesive material to a transfer roller, the said material being of any predetermined thickness, simple and efficient means being employed for regulating the delivery of the adhesive.

Another object is to provide an apparatus which will feed the strip materials therethrough automatically.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings, the preferred form of the invention has been shown.

In said drawings:

Figure 1 is a plan view of the complete machine, the strip material being shown in position therein.

Figure 2 is a side elevation thereof.

Figure 3 is a section on line 3—3, Figure 1.

Figure 4 is a horizontal section through the lower portion of the adhesive container and the bearing rollers adjacent thereto, the said rollers being shown in plan.

Figure 5 is a section through one side of the machine taken on line 5—5, Figure 2.

Referring to the figures by characters of reference, 1 designates the base of the apparatus which can consist of a slab of slate

or other suitable material having parallel plates 2 erected thereon and bridging opposite end portions of an outlet opening 3 formed in the base. This opening is located above a tank 4 adapted to receive surplus adhesive. Located directly above the opening 3 is an adhesive supplying roller 5 the peripheral portion of which is formed of a layer 6 of any suitable material for properly picking up and conveying adhesive applied thereto. The shaft 7 of this roller is journaled in split bearings 8 which are slidable in slots 9 formed in the respective plates 2.

The roller 5 is interposed between and parallel with the feed rollers 10 and 11 each of which has spirally arranged teeth or studs 12 extending from its periphery. Roller 10 is carried by a shaft 13 journaled in split bearings 14 which are mounted in slots 15 in the respective plates 2. Roller 11 rotates with and is supported by a shaft 16. This is also journaled in split bearings 17 mounted in slots 18 formed in the respective plates 2.

Arranged above each of the plates 2 is a lever 19 pivotally mounted at one end as shown at 20 while its other end is adapted to engage and be held by a spring latch 21 or the like as shown particularly in Figure 2. This lever carries adjusting screws 22 each of which has a head or enlargement 23 adapted to bear down upon a spring 24 located above and bearing upon one end of the sets of split bearings. Consequently when lever 19 is moved downwardly and secured in the position shown in Figure 2, the springs 24 will be placed under compression by the respective screws 22 and held so as to yieldingly resist upward sliding movement of the split bearings and the shafts and rollers associated therewith. When the bearings are in their normal or lowermost positions, the roller 5 is located where it will touch the top surface of the backing board B or the like to which adhesive is to be applied. When the rollers 10 and 11 are in their lowermost positions the teeth or studs 12 therein will bite into said board.

The two levers 19 have standards 25 the

upper ends of which are forked as at 26 to receive trunnions 27 extending in opposite directions from the hopper 28. Thus the hopper is suspended with its small or lower 5 end supported between the rollers 5 and 10 and normally out of contact with them. That face of the hopper nearest roller 5 has an outlet opening 29 extending throughout the width thereof at the lower end of the 10 hopper and this opening is closed at the bottom by a strip 30 formed of rubber or the like which has a scraping edge 31 adapted to be supported close to the roller.

A slide 32 is mounted in the hopper and 15 is adapted to be raised and lowered by means of a handle 33 after which it can be held by a set screw 34 or the like. The lower edge and adjacent side portions of slide 32 can be provided with a lip 35 of rubber or 20 other suitable flexible material for sealing the edge portions of the slide at the outlet. By raising and lowering the slide the size of the outlet in the hopper 28 can be varied.

The top of the hopper is adapted to be 25 tightly closed by means of a cover 36 so as to exclude air. This cover may support a guide roller 37. The guide roller is preferably located adjacent to the back end of the cover.

30 A cam 38 is rotatably mounted between the plates 2 and is adapted to be shifted by a lever 39. Under normal conditions the container 28 is balanced by the standards 25 and spaced from the roller 5. By shifting lever 39, however, the cam 38 can be caused to press against the lower portion of hopper or container 28 and force the outlet opening toward the surface of roller 5 with the edge 31 of the rubber strip 30 located either in 35 contact with or at any desired distance from the roller. Thus an adhesive contained in the hopper can gravitate to the surface of the roller and be drawn downwardly thereby, the amount of adhesive released being 40 regulated by the sliding valve 32. By shifting cam 38 the thickness of the film of adhesive on the roller can be varied at will. Surplus adhesive will of course be stopped by the edge 31 of strip 30.

50 Side plates 40 are mounted on the base 1 at points remote from the plates 2 and mounted in them are bearings 41 carrying the shaft 42 of a feed roller 43. This roller has an active surface of rubber or the like 55 for properly gripping the work. Adjustable springs 44 can be provided for thrusting against the bearings 41.

Shaft 42 has a sprocket 45 which is adapted to receive motion through a chain 46 60 from a sprocket 47 secured to the shaft 16.

Another sprocket 48 is secured to shaft 16 and transmits motion through a chain 49 to a sprocket 50 on shaft 7. Shaft 13 is driven by a chain 51 mounted on sprockets 52 and 65 53 secured to the shafts 16 and 13 respective-

ly. An electric motor or other suitable power device indicated generally at 54 is adapted to transmit motion through worm gearing 55 to a shaft 56 which, in turn, transmits motion through sprocket 57 and chain 58 to a sprocket 59 on shaft 16.

In practice a backing board B of any suitable material is placed on the base 1 and positioned so as to bear laterally against a channeled guide member 60 interposed between one of the plates 2 and one of the plates 40. This board will be gripped by the teeth 12 on roller 10 and as the gearing heretofore described constitutes a reduced speed gearing the backing board will be moved slowly under the rollers 10, 5 and 11. As it passes under roller 5 an adhesive will be applied thereto from the surface 6 of said roller. Any surplus adhesive applied to the board or beyond the edge thereof will be delivered through opening 3 into tank 4. A strip of cork or other material to be applied to the backing board, and which has been indicated at C, is fed over hopper 28 where it is supported by a guide roller 37. The forward free end of this strip C is placed on the surface of the advancing backing strip to which adhesive has been applied and the two strips, with the adhesive between them, are then passed under roller 43 which will force them tightly together and feed them forwardly.

The teeth 12 on roller 11 insure positive ejection of the backing strip after it leaves the roller 5 and the gripping action of roller 43 insures positive delivery of all portions of the joined strips.

The teeth or studs on the several rollers will bite into the board being treated. Thus the surface of the board is roughened and the adhesive will become more firmly anchored to the board than would otherwise be possible. Consequently this method of applying the adhesive is superior to the one in which the adhesive is applied by hand.

In addition to the guide strips 60, one or more guide blocks 61 can be adjustably mounted on the base 1 adjacent to one edge of the backing strip, each of these blocks preferably carrying a pin 62 or the like adapted to be seated in any one of a series of recesses 63 in the base. A finger 64 is carried by each pin for adjustment against the adjacent side edge of the backing strip B so as to properly guide it. As roller 37 is located back from the pivotal axis of hopper or container 28, the weight of the supported upper ply will be utilized for maintaining the container normally in a substantially predetermined position relative to roller 6.

What is claimed is:

1. A machine for assembling the plies of laminated boards including a toothed roller for feeding one ply of the board and form-

ing indentations in one surface thereof, a container having an outlet for adhesive, means for transferring adhesive from the outlet of the container to coat the said ply and fill the indentations, means on the container for movably supporting a second ply and maintaining the container normally in a predetermined position, and means for guiding said second ply onto and pressing it upon the coated and indented surface of the other ply.

2. The combination with a base for supporting the lower ply of a laminated board, and a toothed roller for sliding said ply along the base and forming indentations in the top surface thereof, of a tilttable container for adhesive having a bottom outlet, means for transferring adhesive from the outlet to coat the lower ply and fill the indentations, means on the container for movably supporting an upper ply to maintain the outlet normally in a predetermined position relative to the transferring means, and rotatable means for pressing the top ply onto the lower ply and delivering both plies from the machine with the indentations concealed therebetween.

In testimony that I claim the foregoing as my own, I have hereto affixed my signature.

GEORGE G. ALBERT.
